United States Patent Office.

GILBERT DÉCLAT, OF PARIS, FRANCE.

Letters Patent No. 97,613, dated December 7, 1869.

IMPROVED APPARATUS FOR TREATING CROUP AND OTHER DISEASES.

The Schedule referred to in these Letters Patent and making part of the same.

To all whom it may concern:

Be it known that I, GILBERT DÉCLAT, of Paris, France, have invented a new and improved Anti-Croup Apparatus; and I do hereby declare that the following is a full and exact description thereof.

The nature of my invention consists in curing the croup by the action of breathing the vapors of different ingredients herein described, and which vapors are produced by any proper apparatus or any kind of damp-steam pulvizerator.

In 1865, I published a book, in which I indicated carbolic acid as a new medicine, possessing the property of curing parasitic and infectious diseases, especially the croup, diphtheria, angina, (malignant and gangrenous,) the diseases of the chest, the generality of the skin-diseases, &c.

Since then, I have modified the process of employing carbolic acid in the above diseases, and I am now convinced that all parasitic substances, carbolic acid, certain mercurial salts, iodine, sulphur, camphor, &c., generally act with more efficacy and rapidity when they are introduced into the system by inhalation, or into the pores of the skin by wet fumigations produced by the said ingredients.

The process I employ to cure the croup is as follows:

When the water, placed in the bowl of the apparatus, is at boiling-point, add, every two hours, one tea-spoonful of the solution No. 1, and one of the compound mixture No. 2. The water must be kept always boiling.

Solution No. 1 is a strongly-concentrated alcoholic solution of carbolic acid, (alcohol, fifteen parts; carbolic acid, eighty-five parts.)

Mixture No. 2, a mixture of one and one-fourth drachm of cinnabar, or sulphuret of mercury, or any other salt of mercury, of copper, &c., and from one-half to one drachm of parasitic powders, such as the guaco, akentobo, juniper-berry, Spanish chamomile, &c.

Owing to the rapid progress of the croup, it may appear at first sight that this process presents several inconveniences, such as the difficulty of finding at once, and at the same druggist's, the different ingredients and the proper apparatus.

Having foreseen these difficulties, I have found the remedy by combining a box that contains all that is requisite for the operation, and I shall publish its contents in the medical papers, so that all parents desirous of having in store a sure cure for the croup, may find no difficulty in doing so.

Description of an Anti-Croup Apparatus.

The box above mentioned should contain, first, a

holder combined in such a manner as to present the following advantages:

First, it must be very solid, and made so as to be easily fixed to a chimney, a plank, or a night-table.

Second, it must be so manufactured that none of its parts melt under the action of a lamp composed of one or more burners.

Third, it must secure the above lamp, either by means of a hole or by claws, so that the lamp may not be thrown over by the patient or the nurse.

Fourth, it must hold fast, and at a proper distance over the lamp, a bowl in which the water and ingredients are to be boiled.

Fifth, it must act like a chimney, so that the cold air may come from below, and that the hot air may surround the bowl, and keep the contents in a continual boiling state, without any danger of the contents of the lamp exploding.

To obtain the above results, I have adopted—

First, an alcoholic lamp with one or more burners, in preference to a lamp with three burners.

Second, a bowl with a wide opening, so as to have a large surface of evaporation; this bowl to be made of fire-proof porcelain, of varnished clay, or of iron, (not tinned inside,) on account of the action of the ingredients. Hitherto I prefer the latter.

Moreover, the box must contain—

First, several glass tubes to stir up the mixture.

Second, the required ingredients.

Third, several doses of the powder and syrup of ipecacuanha, the syrup to be slightly dosed with carbolic acid, so that it may not ferment and lose its qualities by keeping.

Fourth, and finally, a provision of alcohol for the lamp.

What I claim, therefore, as my invention, and desire to secure by Letters Patent, is—

The application, (at a distance, without any operation or medication,) by inhalation, of the vapors of the different ingredients herein described, or to be described hereafter, (which vapors are produced by any proper apparatus,) to cure the croup, diphtheria, angina, (malignant and gangrenous,) the diseases of the chest, the generality of the diseases of the skin, &c., or any other, substantially the same, and which will produce the intended effect.

DÉCLAT,
80 Rue Taitbout, Paris.
